HEDGE SHEARS OR A SIMILAR ARTICLE

David H. Keiser, Jr., 53 Park Road, Wyomissing Hills,
West Lawn, Pa.

Filed Nov. 29, 1962, Ser. No. 72,656

Term of patent 14 years

(Cl. D22—4)

FIG. 2.

FIG. 3.

FIG. 4.

FIG. 5.

FIGURE 1 is a top plan view of hedge shears, or a similar article, showing my new design;

FIG. 2 is a side elevational view of a portion of the hedge shears, as seen by looking in the direction of the arrow 2—2 on FIG. 1;

FIG. 3 is a bottom plan view of FIG. 2 with the broken line showing being omitted for convenience of illustration;

FIG. 4 is a front end elevational view of FIG. 3; and FIG. 5 is a rear end elevational view of FIG. 3.

The characteristic feature of my design resides in the portions shown in full lines and particularly in the form and configuration of the forward attaching ferrule portion of the handles as shown in full lines.

I claim:

The ornamental design for hedge shears or a similar article, substantially as shown and described.
